APPARATUS FOR SETTING PINS

Henry C. Luebbert, Cleveland, Ohio

Application May 20, 1947, Serial No. 749,136

7 Claims. (Cl. 273—42)

1

This invention relates to apparatus for setting pins in proper position on a bowling alley.

The task of setting pins in proper position on a bowling alley is tedious, difficult and time-consuming if performed manually. On commercial alleys, the time required for manual setting of pins reduces the income receivable from an alley and also is a source of dissatisfaction to bowlers using the alley. On alleys used in the home the difficulty, tedium and time involved in manual setting of the pins detract considerably from enjoyment of the game and, indeed have limited the sale and use of home bowling equipment.

Various forms of apparatus have been proposed for mechanically setting pins on alleys. Such apparatus, however, has invariably been complicated and expensive, and often has not been as efficacious as desired. In general, because of their complicated and expensive construction, such prior forms of apparatus could not be used on home alleys which must be small and inexpensive.

It is an object of this invention to provide apparatus for setting pins in proper position on a bowling alley, which is effective and simple in operation, and which may be of simple and inexpensive construction. Because of these features, the apparatus may be employed at particular advantage on small, inexpensive home alleys, although it may be employed to advantage on regulation size commercial alleys.

It is a further object of this invention to provide such pin-setting apparatus which comprises a vertically reciprocable carriage into which, when the carriage is in its elevated position, pins may be readily manually loaded with no particular care required to place the pins in a particular position. The carriage may then be lowered to a position above the alley where it accurately sets the pins in the desired vertical positions, after which the carriage may be raised to its elevated position, leaving the pins properly set on the alley.

It is another object of this invention to provide pin-setting apparatus in which each pin loaded in the carriage is positioned in wedging relation with respect to a slide member, which slide member is unlocked when the carriage reaches its pin-setting position to permit each pin to wedge the slide member to releasing position, freeing the pin and thereby setting it.

The apparatus of the invention includes a vertically reciprocable carriage comprising a generally horizontally disposed guide member, which has a plurality of pin-depositing openings, and a

2

slide member which is slidably mounted in the carriage below the guide member. The carriage is mounted over the end of the alley so that it may be raised to a pin-receiving position which leaves the space below it unobstructed for bowling purposes; when lowered to a position immediately above the alley, the carriage automatically sets the pins. This automatic action is accomplished by means of the slide member which 5 partially obstructs the openings through the guide member when said carriage is at the upper limit of its travel and slides out of the way to leave said openings unobstructed when the carriage is at the lower limit of its travel, thereby 10 setting the pins. The apparatus also includes means operating as the carriage moves toward its uppermost position, for sliding and locking the slide member in the upper pin-receiving position where it partially obstructs the openings in 15 the guide member. Means are provided for automatically unlocking the slide member as it approaches its lowermost position. The relationship of the parts is such that when the carriage is in its elevated position the pins carried there- 20 by are disposed in a wedging relation with respect to the slide member; as the carriage approaches its lower pin-setting position and the slide member is unlocked, the weight of the pins wedges the slide member to pin-releasing position, leaving the pin-depositing openings in the guide member unobstructed. Only the wedging action of the pins is required to move the slide member to its pin-releasing position. Upon such movement of the slide member the pins drop to 25 the desired position on the alley, being guided by the pin-depositing openings in the guide member.

Advantageously, the supporting means for the carriage embodies means for counterweighting the carriage to offset at least part of the weight of the carriage and render it more easily reciprocable.

From the foregoing general description, it should be apparent that the automatic operation of the apparatus is effected by the weight of the pins themselves and no other force, increased or otherwise, is required. The apparatus operates quickly but smoothly and with a minimum of shock, due in part to the absence of a multiplicity of moving parts which, in prior art devices, had to be cocked or biased. Thus, the apparatus may be of a simple and inexpensive construction requiring a minimum number of parts, none of which requires adjustment from time to time during use. Because of its simple and its

light but rugged construction, it withstands hard usage with a minimum of maintenance.

These and other objects, features and advantages of the present invention will be apparent from the following description of the preferred embodiment in connection with the accompanying drawings and from the claims.

In the drawings,

Fig. 1 is a side elevation of a portable home bowling alley comprising pin-setting apparatus embodying the present invention;

Fig. 2 is a plan view of the apparatus shown in Fig. 1;

Fig. 3 is an end elevation from line 3—3 of Fig. 1, to a scale larger than that of Fig. 1, the pins and backstop being omitted from this elevation for the sake of clearness and the carriage being shown in full lines in its uppermost position and in broken lines in its lowermost position.

Fig. 4 is a plan view of the pin-setting carriage when it is in its elevated position with the slide member partially obstructing the pin-depositing openings, the pins being omitted for the sake of clarity;

Fig. 5 is a corresponding plan view of the pin-setting carriage in its lowermost pin-setting position with the slide member positioned so that the pin-depositing openings are unobstructed for pin-setting purposes, the pins being omitted for the sake of clarity;

Fig. 6 is a sectional elevation along line 6—6 of Fig. 4, showing the pins deposited in wedging relation in the carriage when it is in its elevated position;

Fig. 7 is a detail elevation along line 7—7 of Fig. 6 showing the latching lever for the slide member in the position in which it locks the slide member;

Fig. 8 is a sectional elevation along line 8—8 of Fig. 5 showing the carriage in its lowermost position in which it sets pins on the alley; and

Fig. 9 is a sectional elevation along line 9—9 of Fig. 8 showing the latching lever for the slide member in unlocked position.

The bowling pin-setting apparatus disclosed comprises a longitudinally extending horizontally disposed alley member 10, a vertical member 20, and a vertically reciprocable pin-setting carriage 30 supported from member 20. The carriage 30 is normally positioned in an elevated position in which it leaves the alley floor unobstructed, as shown in full lines in Fig. 1. When so positioned the carriage is adapted to have pins easily loaded therein. The carriage 30 is capable of being moved downwardly to its lowermost position on or immediately above the end of the alley floor, as shown in broken lines in Fig. 1, in which position it sets the pins in proper position on the alley. The carriage is capable of being then moved upwardly to its elevated position.

In the illustrated embodiment, the alley member 10 comprises spaced parallel longitudinally extending side members 11 and a smooth alley floor 12 extending from the ball-delivery end or front end to the pin end or rear end of the apparatus. Said floor 12 extends between, and at the pin end of said floor beyond, said side members 11. Ball return gutters 13 are provided at the sides of the floor 12; if desired, the floors of the gutters may be inclined toward the ball-delivery end of the alley member to cause balls in the gutters to return to said end when placed in the gutters.

The vertical member 20 of the illustrated em-

bodiment comprises spaced vertically extending side members 21, each of which has a vertically extending portion 22 and a lower longitudinally extending portion 23. The alley floor 12 extends between the longitudinally extending portions 23, and the side members 11 are detachably connected thereto, as by hook means 24. The alley member 10 thus may be disconnected from and removed from the vertical member 20, to save space for shipping or storage purposes. Because of the forward projection of the lower portions 23 of members 21 and the rearward projection of members 25 fixed to the rear of members 21, the vertical member 20 stands firmly on the floor supporting the apparatus and resists tipping, even when disconnected from alley member 10.

Each of members 21 has fixed to its inner surface a vertically extending beam 26. Each of said beams 26 terminates a sufficient distance above the bottom of member 21 to clear the alley member 10, and extends upwardly for a sufficient distance to carry the means for supporting carriage 30. The lower portions of beams 26 act as guides for the vertically reciprocable carriage 30.

Upper cross member 27 and intermediate cross member 28 fixed to the vertical beams 26, and lower cross member 29 fixed to the lower rear portions of side members 21, provide rigidity of the vertical member 20.

As shown in Figs. 2, 4 and 5, the illustrated carriage 30 in plan view, is of the general configuration of a triangle of sufficient size to encompass the triangular area in which the bowling pins are to be disposed when properly positioned on the alley floor 12. It comprises a rigid frame 31 comprising vertical walls arranged in the general form of a triangle having at its rear or base portion parallel walls 32. For lightness, strength, and freedom from warping the illustrated frame 31 is built of plywood boards rigidly fastened together. The rear wall of the frame 31 is provided with laterally projecting portions 33, formed in the illustrated case by extensions of the board forming the rear wall of the frame 31. The rear surfaces of these projecting portions 33, and the outer surfaces of vertical members 34, fixed thereto, contact the front and inner surfaces of vertical members 26 with a loose sliding fit to guide the frame 31 vertically.

As is apparent from Figs. 4, 5, 6 and 8, the frame 31 has rigidly mounted therein a guide plate 35. Said plate has therethrough a plurality of circular openings 36 located to provide the proper relative position and spacing of the bowling pins on the alley floor 12. Each of these openings is slightly larger than the maximum diameter of the pins employed, being sufficiently large to permit the pins to pass smoothly therethrough, but not so large as to permit mislocation of the pins.

In the embodiment under discussion, guide plate 35 is formed of a thick piece of wood, such as balsa wood to provide lightness, which rests upon a plurality of lugs 37 fixed to the inner sides of the frame 31. The plate 35 may be permanently fixed in the frame 31, or may be removably but rigidly mounted therein.

Slidably mounted in the frame 31 below the guide plate 35 is slide member 40, in the illustrated embodiment taking the form of a plywood board, of generally triangular shape having flat parallel sides 41 near its base. The board has therethrough recesses 42 and 43, shaped and located as hereinafter described.

Said slide member 40 is freely slidably sup-

ported on cross members 38 extending across the lower portion of frame 31 and fixed to the sides thereof. It is capable of being moved toward the front or apex and toward the rear or base of frame 31, being guided by contact of its flat sides 41 with the parallel walls 32 of frame 31.

The recesses 42 and 43 are so shaped and positioned that when the slide member 40 is at the rearward limit of its travel, the openings 36 of said guide plate 35 are wholly unobstructed, but when the slide member 40 is at the forward limit of its travel, the rear portion of each of the openings 36 is partially obstructed by an edge 44 of one of the recesses 42 or 43. In the illustrated embodiment, the recesses 42 take the form of rectangular openings, whereas the recess 43 at the apex of the slide member 40 take the form of an indentation. The edges 44 are shown as being straight, for simplicity in construction, but they may be of other configuration, as curved concavely.

As shown to advantage in Figs. 4 and 6, the parts are so proportioned that when the slide member 40 is in its extreme forward position and each of its edges 44 partially obstructs one of the openings 36 in guide plate 35, the distance that the central portion of the edge 44 projects beyond the rear portion of the openings 36, and the distances between the edge 44 and the front and rear upper rim portions of opening 36, are such that when a blowing pin 1 is placed in the partially obstructed opening 36, it is supported by contact of its lower upwardly swelling portion with the front wall of opening 36, the rear upper rim of said opening, and edge 44. The bowling pin is thus supported in wedgeing relation tending to force the slide member 40 rearwardly. Preferably, the parts are so proportioned that when the pin is so held its center of gravity is below the top surface of guide plate 35, and hence the pin has no tendency to topple. As is shown in Figs. 5 and 8, when the slide member 40 is moved to its rearmost position, the openings 36 are wholly unobstructed and the pins 1 therein can pass freely therethrough.

Rotatably but nonslidably connected to a lug 45 fixed to the central rear portion of slide member 40, is a double bell crank latching lever 50, shown to advantage in Figs. 3-9. Said lever comprises a shaft portion 51 which is rotatably but nonslidably connected to said lug 45 and extends in the direction of travel of slide member 40 through the rear wall of frame 31. The lever 50 also includes a latching portion at right angles to shaft portion 51, comprising a portion 52, a portion 53 substantially at right angles to both portions 51 and 52, and a terminal portion 54 substantially at right angles to portion 53 and approximately parallel to portion 52, as shown. A lock member 55, taking the form of a yoke member, is mounted on the rear wall of frame 31. Yoke member 55 is adapted to receive in its slot the portion 52 of latching lever 50 and hold it in an approximately horizontal position. The parts are so arranged that when the portion 52 of the lever 50 is so positioned in the yoke member 55, the slide member 40 is in its forward position and is locked there.

As shown in Figs. 1, 2 and 3, the carriage 30 is suspended by three cables 60 connected to the corners of the frame 31 and to a cable 61. Cable 61 passes over sheave 62 supported from upper cross member 27 of frame 20, around sheave 63 on said cross member, over sheave 64 above one of vertical beams 26, and is connected to a coun-

terweight 65. Sheave 62 is so located with respect to carriage 30 suspended therefrom that the carriage 30 presses against the guide portions of vertical beams 26, whereby the carriage 30 is accurately guided in its upward and downward travel. The apparatus shown also comprises two spaced vertical members 66 fixed to the beam 26 adjacent which the counterweight 65 is disposed, to serve as a guide and guard for the counterweight.

The counterweight 65 serves to offset at least part of the weight of the carriage 30 and render it easily reciprocable. Preferably the counterweight 65 is heavy enough to overcome the weight of the empty carriage and the frictional resistance in the sheaves so that after the carriage has set the pins on the alley floor, the empty carriage 30 is capable of being moved to its uppermost position by the counterweight 65.

20 In the embodiment under discussion, a stop member 67 is positioned on cable 61 immediately above the counterweight 65. Figs. 1 and 3 show manually operable latch member 68, adapted to engage stop member 67, mounted on the lower portion of guide members 66 in such position as to hold the counterweight 65 in its lowermost position and the carriage 30 in its uppermost position when it is loaded with pins. The illustrated latch member 68 comprises cross member 69 fixed to the guide members 66, an upwardly extending spring member 70 fixed at its lower end to cross member 69 and having a hook portion at its upper end adapted to engage stop member 67, and a handle portion 71 connected to the upper portion of spring member 70 whereby the hook portion of the spring member may be manually drawn out of engagement with stop member 67 to release the cable 61.

As shown in Figs. 3, 4, and 6, the intermediate 40 cross member 28 of vertical member 20, which cross member is properly located for the purpose, is provided on its inner surface with a cam member 80. The illustrated cam member 80 is formed of spring metal shaped and positioned to contact the lever 50 in the vicinity of the portion 51 thereof projecting from the rear wall of frame 31 of carriage 30, and to move the protruding portions of the lever 50 toward the frame 31 as the carriage 30 moves upwardly into its uppermost position.

50 Cross member 28 also includes on its inner surface a stop member 81 which is positioned so that its underside engages terminal portion 54 of lever 50 and moves latch portion 52 downwardly into yoke member 55. Therefore, as the carriage 30 moves upward into its uppermost position, cam member 80 and stop member 81 cooperate to move the latching lever 50 inwardly with respect to the frame 31 of carriage 30, and to lock the latch portion 52 of crank 50 in yoke member 55, thus moving the slide member 40 to its forward position and locking it there.

The lower cross member 29 of vertical member 20 has mounted thereon a stop member 82, shown 65 to advantage in Figs. 3, 8 and 9. Said stop member 82 is positioned so that its upper portion engages the terminal portion 54 of lever 50 and lifts the portion 52 out of yoke member 55, as the carriage 30 moves downwardly to its lowermost position, in which it rests on or is immediately above the alley floor 12. The weight of the pins 1 in the carriage then causes the slide member 40 to shift to its rearward position in the carriage, thus moving the lever 50 to its outward 70 position.

The embodiment under discussion includes also a backstop member 90 adapted to stop the bowling balls at the pin end of the alley; such backstop member is shown in Figs. 1 and 2, but is omitted from other figures for the sake of clearness. The illustrated backstop member 90 comprises side members 91 connected to rearwardly projecting members 25, cross member 92 fixed to side members 91, and a stop board 93, formed of fiber board, or the like, supported by cross member 92.

The operation of the apparatus described above is as follows: When the apparatus is ready for bowling purposes, the pins 1 are standing in the proper position on the alley below the carriage 30. The carriage 30, which is empty, is in its elevated position, being held there by the weight of the counterweight 65. The latch portion 52 of latching lever 50 is held in yoke member 55; the slide member 40 is therefore locked in its forward position and its edges 44 partially obstruct the openings 36 in guide plate 35, described above.

After bowling, when it is desired to re-set the pins 1, the pins are loaded in the carriage 30 when it is in the elevated position by being manually placed in openings 36 of the guide plate 35 of the carriage 30. It is a simple matter to place the pins in said openings, since no particular care is required. As the pins drop into the openings 36, they orient themselves as shown in Figs. 1, 2 and 6 so that each pin is tilted toward the rear of the carriage 30 and is supported by contact of its upwardly swelling lower portion with the front wall of the opening 36 in which the pin is disposed, the upper rear rim of said opening, and the edge 44 of slide member 40 partially obstructing said opening and containing the pin in wedging relation.

When it is desired to lower the carriage 30 of the illustrated apparatus, the handle portion 71 of latch member 68 is pulled rearwardly or away from vertical member 20 to disengage the hooked portion of the spring member 70 from the stop member 67 on cable 61 and permit the carriage 30 loaded with pins 1 to be moved downwardly. As the carriage 30 approaches the floor 12 of the alley member 10, the terminal portion 54 of latching lever 50 contacts stop member 82 on lower cross member 29, and latch portion 52 of the lever 50 is raised out of yoke member 55, thus releasing the lever 50 and unlocking slide member 40. The weight of the tilted pins 1 is sufficient to, and does, move the slide member rearwardly in carriage 30, until the edges 44 of slide member 40 no longer obstruct the openings 36 in guide plate 35 of carriage 30 and the lever 50 is pushed outwardly of carriage 30. The pins 1 therefore drop through said openings 36, being guided thereby, until they rest vertically on the alley floor 12 in the proper positions.

The empty carriage 30 is then moved upwardly. As the carriage 30 approaches its uppermost position, the portion of latching lever 50 adjacent the projecting end of portion 51 of the lever contacts the cam member 80 on cross member 28 and is moved inwardly of carriage 30 to a position where latch portion 52 of lever 50 is aligned with the slot in yoke member 55 on frame 31 of carriage 30. Meanwhile, the terminal portion 54 of said lever contacts stop member 81 on said cross member 28, and is moved downwardly until latch portion 52 of lever 50 is seated in the slot of yoke member 55. Such motion of lever 50, of course, results in moving the slide member 40 to its for-

ward position and locking it in such position; in this position, the edges 44 of the slide member 40 partially obstruct the openings 36 through the guide plate 35 of the carriage 30, as described above.

Meanwhile, as the counterweight 65 reaches its lowermost position, the stop member 67 on cable 61 engages the hooked portion of the spring member 70 of latch member 68.

The pins 1 are thus set in the desired positions on the alley floor 12, and the carriage is again ready to be loaded.

By proper proportioning of the weights of the carriage 30 and counterweight 65, and proper choice of the length of the cable 61, the carriage 30 can be made to halt at its uppermost position solely by the contact of the lever 50 with the cam member 80, the stop member 81, and yoke member 55.

The present invention thus provides apparatus for setting pins on bowling alleys which is simple, rugged and inexpensive in construction, which may be made of readily available materials, and which does not readily get out of order. For these reasons, apparatus embodying the invention may be employed to particular advantage on home bowling alleys.

Other embodiments of the invention than the one described above, and various modifications of the illustrated embodiment of the invention may be made without departing from the invention. The invention, therefore, is not to be limited to the embodiments disclosed, but is to be limited solely by the scope of the appended claims.

What is claimed is:

1. Pin-setting apparatus for a bowling alley comprising a vertically reciprocable carriage comprising a generally horizontally disposed guide member having a plurality of openings therethrough each adapted to guide a bowling pin therethrough; a slide member slidably mounted below said guide member in said carriage and having pin-supporting portions, each of which, when said slide member is at one end of its travel in pin-supporting position, partially obstructs one of said guide openings and cooperates with said opening to support a bowling pin by its upwardly swelling lower slide portion in wedging relation tending to force said slide member away from its partially-obstructing, pin-supporting position, and when said slide member is at the other end of its travel in pin-releasing position, leaves said guide opening unobstructed; means for supporting said carriage so that it may be raised to an upper position where it leaves the space below it unobstructed for bowling purposes, and lowered to a lower position where it sets pins carried thereby; means for sliding said slide member to pin-supporting position and locking it in said position as said carriage moves upward toward its upper position; and means for unlocking said slide member as it approaches its lower position, whereby the wedging action of pins supported in wedging relation in said guide openings moves said slide member to pin-releasing position and permits said pins to be set in position.
2. Pin-setting apparatus for a bowling alley comprising a vertically reciprocable carriage comprising a generally horizontally disposed guide member having a plurality of openings therethrough each adapted to guide a bowling pin therethrough; a slide member slidably mounted below said guide member in said carriage

riage and having pin-supporting portions, each of which, when said slide member is at one end of its travel in pin-supporting position, partially obstructs one of said guide openings and cooperates with said opening to support a bowling pin by its upwardly swelling lower side portion in wedging relation, and when said slide member is at the other end of its travel in pin-releasing position, leaves said guide opening unobstructed; means for supporting said carriage so that it may be raised to an upper position where it leaves the space below it unobstructed for bowling purposes, and lowered to a lower position where it sets pins carried thereby; means for sliding said slide member to pin-supporting position and locking it in said position as said carriage moves upward toward its upper position; means for unlocking said slide member as it approaches its lower position and permitting said slide member to be moved to its pin releasing position by the wedging action of said wedging relation after it has been unlocked, to permit pins carried by said carriage to be set in position, said unlocking means comprising a fixed stop against which said means for locking said slide member in its pin supporting position bears when said slide member approaches its lower position.

3. Pin-setting apparatus for a bowling alley comprising a stationary support; a carriage vertically reciprocable with respect to said support and comprising a generally horizontally disposed guide member having a plurality of openings therethrough each adapted to guide a bowling pin therethrough; a slide member slidably mounted below said guide member in said carriage and having pin-supporting portions, each of which, when said slide member is at one end of its travel in pin-supporting position, partially obstructs one of said guide openings and cooperates with said opening to support a bowling pin by its upwardly swelling lower side portion in wedging relation tending to force said slide member away from its partially obstructing pin-supporting position, and when said slide member is at the other end of its travel in pin-releasing position, leaves said guide opening unobstructed; means carried by said support for raising said carriage to an upper position where it leaves space below it unobstructed for bowling purposes, and for lowering said carriage to a lower position where it sets pins carried thereby, said means including a counterweight for the carriage which is heavier than the carriage free of bowling pins; means for sliding said slide member to pin-supporting position and locking it in said position as said carriage moves upward toward its upper position; means for unlocking said slide member as it approaches its lower position whereby said pins carried by said carriage move said slide member to pin-releasing position after it has been unlocked to permit said pins to be set in position and said carriage, free of the weight of the pins, is capable of being returned to its upper position by said counterweight.

4. Pin-setting apparatus for a bowling alley comprising a frame having a generally vertically extending carriage-supporting portion; a pin-setting carriage mounted for vertical reciprocation on said frame portion, said carriage comprising a frame, a generally horizontally disposed guide member in said carriage frame having therethrough a plurality of circular openings each of a diameter slightly larger than the diameter of the bowling pins to be set, and a slide member slidably mounted in said carriage

frame below said guide member having pin-supporting portions each of which, when said slide member is at one end of its travel in pin-supporting position, partially obstructs one of said guide openings and cooperates with said opening to support a bowling pin by its upwardly swelling lower portion in wedging relation, and when said slide member is at the other end of its travel in pin-releasing position leaves said guide opening unobstructed; a bell crank lever having a shaft extending in the direction of travel of said slide member and rotatably but non-slidably connected to said slide member and having a first arm portion, and a latching arm portion extending at right angles to said first arm portion; a lock member on said carriage frame for receiving said latching arm portion of said bell crank lever to lock said slide member in pin-supporting position; means on said apparatus frame for engaging said latching arm portion of said bell crank lever to move said slide member to pin-supporting position and said latching arm into said lock member, as said carriage moves upwardly into its upper position; means on said apparatus frame for engaging said latching arm portion of said bell crank lever and disengaging it from said lock member to release said slide member as said carriage reaches its lower position, whereby the wedging action of the pins supported in wedging relation in said slide member moves said slide member to pin-releasing position and permits the pins to be set in position.

5. Pin-setting apparatus for a bowling alley comprising a frame having a generally vertically extending carriage-supporting portion; a pin-setting carriage mounted for vertical reciprocation on said frame portion, said carriage comprising a frame, a generally horizontally disposed guide member in said carriage frame having therethrough a plurality of circular openings each of a diameter slightly larger than the diameter of the bowling pins to be set, and a slide member slidably mounted in said carriage frame below said guide member having pin-supporting portions each of which, when said slide member is at one end of its travel in pin-supporting position, partially obstructs one of said guide openings and cooperates with said opening to support a bowling pin by its upwardly swelling lower portion in wedging relation, and when said slide member is at the other end of its travel in pin-releasing position leaves said guide opening unobstructed; a bell crank lever having a shaft extending in the direction of travel of said slide member and rotatably but non-slidably connected to said slide member and having a first arm portion, and a latching arm portion extending at right angles to said first arm portion; a lock member on said carriage frame for receiving said latching arm portion of said bell crank lever to lock said slide member in pin-supporting position; means on said apparatus frame for engaging said latching arm portion of said bell crank lever to move said slide member to pin-supporting position and said latching arm into said lock member, as said carriage moves upwardly into its upper position; means on said apparatus frame for engaging said latching arm portion of said bell crank lever and disengaging it from said lock member to release said slide member as said carriage reaches its lower position, whereby the wedging action of the pins supported in wedging relation in said slide member moves said slide member to pin-releasing position and permits the pins to be set in position.

11

the pins to be set in position, said apparatus frame carrying a counterweight for the carriage which is heavier than the carriage free of bowling pins, whereby after said carriage sets pins while in its lower position and is freed of the weight of the pins, said carriage is capable of being returned to its upper position by said counterweight.

6. Pin-setting apparatus for a bowling alley comprising a frame having a generally vertically extending carriage-supporting portion; a pin-setting carriage mounted for vertical reciprocation on said frame portion, said carriage comprising a frame, a generally horizontally disposed guide member in said carriage frame having therethrough a plurality of circular openings each of a diameter slightly larger than the diameter of the bowling pins to be set, and a slide member slidably mounted in said carriage frame below said guide member having pin-supporting portions each of which, when said slide member is at one end of its travel in pin-supporting position, partially obstructs one of said guide openings and cooperates with said opening to support a bowling pin by its upwardly swelling lower portion in wedging relation, and when said slide member is at the other end of its travel in pin-releasing position leaves said guide opening unobstructed; a bell crank lever having a shaft extending in the direction of travel of said slide member and rotatably but non-slidably connected to said slide member and having a first arm portion, and a latching arm portion extending at right angles to said first arm portion; a lock member on said carriage frame for receiving said latching arm portion of said bell crank lever to lock said slide member in pin-supporting position; means on said apparatus frame for engaging said latching arm portion of said bell crank lever to move said slide member to pin-supporting position and said latching arm into said lock member, as said carriage moves upwardly into its upper position; means on said apparatus frame for engaging said latching arm portion of said bell crank lever and disengaging it from said lock member to release said slide member as said carriage reaches its lower position and permit said slide member to move to its pin-releasing position after it has been unlocked, to permit pins carried by said carriage to be set in position, said apparatus frame carrying a counterweight for the carriage which is heavier than the carriage free of bowling pins, whereby when said carriage sets pins while in its lower position and is freed of the weight of the pins, said carriage is capable of being returned to its upper position by said counterweight.

7. Pin-setting apparatus for a bowling alley comprising a frame having a generally vertically extending carriage-supporting portion; a pin-setting carriage mounted for vertical reciprocation on said frame portion, said carriage com-

12

prising a frame, a generally horizontally disposed guide member in said carriage frame having therethrough a plurality of circular openings each of a diameter slightly larger than the diameter of the bowling pins to be set, and a slide member slidably mounted in said carriage frame below said guide member having pin-supporting portions each of which, when said slide member is at one end of its travel in pin-supporting position, partially obstructs one of said guide openings and cooperates with said opening to support a bowling pin by its upwardly swelling lower portion in wedging relation, and when said slide member is at the other end of its travel in pin-releasing position leaves said guide opening unobstructed; a bell crank lever having a shaft extending in the direction of travel of said slide member and rotatably but non-slidably connected to said slide member and having a first arm portion, and a latching arm portion extending at right angles to said first arm portion; a lock member on said carriage frame for receiving said latching arm portion of said bell crank lever to lock said slide member in pin-supporting position; means on said apparatus frame for engaging said latching arm portion of said bell crank lever to move said slide member to pin-supporting position and said latching arm into said lock member, as said carriage moves upwardly into its upper position; means on said apparatus frame for engaging said latching arm position of said bell crank lever and disengaging it from said lock member to release said slide member as said carriage reaches its lower position and permit said slide member to move to its pin-releasing position after it has been unlocked, to permit pins carried by said carriage to be set in position, said apparatus frame carrying a counterweight for the carriage which is heavier than the carriage free of bowling pins, whereby when said carriage sets pins while in its lower position and is freed of the weight of the pins, said carriage is capable of being returned to its upper position by said counterweight.

HENRY C. LUEBBERT.
